MECHANICAL IMPULSE REPEATER

John William McClew and Cecil Robert Woodland, Liverpool, England, assignors to Associated Telephone and Telegraph Company, Chicago, Ill., a corporation of Delaware

Application May 15, 1936, Serial No. 79,830
In Great Britain June 11, 1935

24 Claims. (Cl. 179—16)

The present invention relates to automatic telephone or like impulse sending systems and is more particularly concerned with apparatus for correcting the character and speed of trains of electric impulses used in such systems. The object of the invention is to provide an impulse repeater or regenerator which will be capable of receiving incoming impulses and sending out regenerated impulses simultaneously, the two operations taking place entirely independently. The attainment of this object is simplified by the use of a registering and sending device in which the length of a train of outgoing impulses is determined by a mechanical marking corresponding to the received train rather than by an electrical marking as is more usual. A device of this type is employed in carrying out the invention and for convenience it will hereafter be referred to as a mechanical impulse repeater.

According to one feature of the invention in a mechanical impulse repeater for use in telephone or like impulse sending systems, in accordance with the number of impulses in each of a succession of trains of incoming impulses appropriate ones of a plurality of movable members are caused to move from their normal position and thereby determine the number of outgoing impulses to be transmitted in successive trains, each member on restoration to normal enabling the transmission of the next train of outgoing impulses to take place.

According to another feature of the invention a mechanical impulse repeater for use in telephone or like impulse sending systems comprises in combination an electromagnet arranged to respond to incoming impulses and to control the operation of a setting device in accordance therewith, a device arranged to be moved at the end of a train of impulses to effect a marking in accordance with the position which the setting device then occupies and a further electromagnet which controls the initiation of the transmission of a train of outgoing impulses which are correct as regards speed and ratio.

A further feature of the invention is that in a mechanical impulse repeater for use in telephone or like impulse sending systems, incoming trains of impulses operate a single registering device which subsequently controls the transmission of similar trains of impulses correct as regards speed and ratio, the registering device being effective to register a train of impulses while a previous train is still being transmitted.

The invention will be better understood from the following description of one method of carry-

ing it into effect reference being had to the accompanying drawings comprising Figs. 1-5.

Fig. 1 shows suitable circuit connections for a repeater of the mechanical construction according to the invention, and the remaining figures show various views of a practical form of the mechanism, of which

Fig. 2 is a front view of the device showing a transmitting disc 13 mounted for counter-clockwise rotation, a pin-resetting lever 45 mounted upon the disc, a set of impulsing springs 50 operated by the cam 29 during rotation of the transmitting disc, and a fly-ball governor 31 for controlling the speed of rotation of the cam.

Fig. 3 is a rear view of the device showing a ratchet wheel 9, an impulse receiving magnet 1 for stepping the ratchet wheel, a pin-setting (or marking) magnet 2 with its associated armature 6 and a pin-resetting (or transmitting) magnet 3 with its associated armature 10.

Fig. 4 is a plan view of the device showing a reset pin 24, carried by the transmitting disc, which is engaged at its notched end with a stop pin 14 (one of a circle of pins each of which may be displaced independently of the others into the path described by the reset pin during rotation of the transmitting disc) thereby preventing rotation of the disc.

Fig. 5 is a sectional view taken along the line V—V of Fig. 4 showing a pin-setting lever 38 which is affixed to the ratchet wheel 9 for rotation thereby and which may be actuated by armature 6 of the pin-setting magnet to displace pin 14 to the left and consequently into the path of the reset pin 24. This figure also shows the mechanism including a rod 36 for actuating the resetting lever 45 and the reset pin 24 responsive to energization of the pin-resetting magnet thereby to restore a displaced stop pin to the right and permit the transmitting disc to resume its rotation.

Referring now in greater detail to the mechanical construction of the impulse correcting device as shown in Figs. 2-5, it will be seen that the fixed disc 12 takes the form of a rectangular U-shaped mounting plate carrying a circle of displaceable pins 14. The impulse receiving disc is a ratchet wheel 9 having associated with it a movable collar 32 which by means of the collar pins 34 can be caused to tilt the pin-setting lever 38 about its pivot 33 when the marking or pin-setting magnet 2 actuates its armature 6. In Fig. 5 armature 6 is shown in the operated position in which lever 38 is clear of the pins 14. The ratchet wheel 9 is secured to one end of

a tubular spindle 35 supported in a bush 37 which is secured to the frame plate 12. The opposite end of the spindle is fastened to the centre of a clock spring 17 contained in a cup 11 secured to 5 the transmitting disc or gear wheel 13 which is carried on ball bearings 16 also mounted on the bush 37.

The receiving magnet 1 responds to incoming impulses and rotates the ratchet wheel 9 step 10 by step by means of the armature 26 and the pawl 27. The movement of the ratchet wheel rotates the shaft 35 and stores up energy in the clock spring 17 secured to the other end of the spindle. The movement of the armature 26 takes 15 place against the tension of the spring 4 while the pawl 27 is kept in engagement with the ratchet wheel 9 by the spring 38. When the magnet is de-energised at the end of each impulse, the ratchet wheel 9 is rotated one step by the action 20 of the spring 4. The travel of the armature and pawl can be adjusted by the eccentric stops 23 and 28 respectively. The marking magnet 2 is energised throughout each series of impulses and by means of its armature 6 which is provided 25 with a forked end slides the collar 32 along the shaft 35 so as to tilt the pin-setting lever 39 out of engagement with the pins 14 against the action of spring 40. Since the marking magnet 2 remains operated throughout the series of impulses, 30 the lever 39 which is secured to the shaft 35 does not obstruct its movement of engaging any of the pins.

At the end of the series of impulses, the ratchet wheel 9 is retained by the fixed detent 8 in the 35 position to which it has been set, and when magnet 2 de-energizes armature 6 restores thereby permitting lever 39 to move to the left under the action of spring 40. Lever 39 then pushes the particular stop pin opposite which it has stopped 40 through the plate 12 into the path of the reset pin 24 which is attached to but insulated from the transmitting gear wheel 13. Gear wheel 13 is prevented from following the ratchet wheel 9 under the influence of the spring 17 because the 45 reset pin 24 is held by the stop pin pushed into its path at the completion of regeneration on the previous call. This can be better appreciated from Fig. 4 since in Fig. 5 for purpose of clarity the associated pin has been shown in the normal position which would allow the transmitting disc 50 13 to rotate. It will be noticed from Fig. 4 that the end of the reset pin is stepped and the purpose of this will be more fully appreciated later.

The transmitting magnet 3 is provided with an armature projection 10 which is insulated from 55 the armature proper and which when operated tilts the insulated pin reset lever 45 about its pivot 46 to the right by means of an insulated pin 36 taken through the hollow spindle 35. Electrical contact between pin 36 and the spindle is 60 prevented by the use of insulating washers 22 at each end of the spindle and contact between the spindle and the pin reset lever 45 is prevented by use of an insulating stud 20 mounted on the 65 left-hand end of the spindle. The pin 36 is electrically connected to the outside off-normal spring 16 which is insulated from the frame and co-operates with the inside spring 21 which is electrically connected to the frame. Both these 70 springs are secured to the spindle 35 and they are permitted to close by the insulated buffer 41 as soon as the spindle 35 is rotated by the operation of the magnet 1. The buffer 41 is secured to the insulated bracket 42 supporting the reset pin 24 which is initially prevented from rotating

by its engagement with the appropriate pin 14. Electrical connection to the pin 24 is made by way of the spring 25 and the pin reset lever 45. The frame plate 12 is insulated from the main mounting plate 44 by a thin layer 43 of fibre or 5 like insulating material.

When the magnet 3 is operated which as will be described later takes place due to the completion of a circuit over the normally closed transmitting magnet springs 1, armature extension 10, pin 36, off-normal springs 16 and 21, digit stop pin 14, reset pin 24, and spring 25, the pin reset lever 45 pushes the reset pin 24 to the right and this resets the digit stop pin to its normal position out of the path of the reset pin. 15 The gear wheel 13 is prevented from moving as long as the magnet 3 is energized since the stepped position of the reset pin 24 still engages the restored pin 14. When the magnet is de-energised however, the reset pin is restored to 20 normal by the helical spring 47, the gear wheel 13 is freed and under the influence of the stored energy in the spring 17 it rotates in the same direction as the ratchet wheel 9 until the reset pin 24 encounters the digit stop pin which was displaced at the end of the first digit. The gear wheel 13 drives a pinion carrying an impulse cam 29 which during rotation actuates the impulse spring 50 and transmits a train of impulses 25 similar to those received except they will now 30 be of the correct character as regards ratio and speed. The speed is controlled by an adjustable fly-ball governor 31 carried on bracket 19 and driven through worm wheel 18. The governor cup is threaded and can thus be moved axially 35 by rotating it. The inside of the cup is slightly conical and hence altering its position will alter the radius at which the governor wings engage and thus alter the speed. The governor cup is locked in any desired position by a flat spring 30 bearing on its serrated surface. The purpose of the holes provided in gear wheel 13 as shown in Fig. 2 is to lighten it and thus reduce its inertia.

When the reset pin 24 on gear wheel 13 encounters the stop pin corresponding to the first 45 digit, the rotation is arrested and an electrical circuit through the pins is again completed to initiate a timing operation for determining the length of interdigital pause. After this has expired, magnet 3 is again energised and the gear 50 wheel 13 is again released and rotates until the reset pin 24 reaches the stop pin corresponding to the next digit, thus sending a series of regenerated impulses corresponding to the second digit. The process is repeated until all the digits have been 55 dealt with when the gear wheel 13 will again catch up with the ratchet wheel 9 and the off-normal springs 16 and 21 are opened to prevent further sending.

Considering now the operation of the device 60 with relation to the repeater circuit shown in Fig. 1, when the repeater is taken into use, relay A operates over the line conductors and at armature *a1* operates relay B. As a result, armature *b1* earths the P conductor to guard the circuit 65 and hold the preceding switches, armature *b2* prepares the impulsive circuit, armature *b4* closes a point in the outgoing loop and armature *b5* completes a circuit for relay IP. Relay IP upon operating, at armature *ip1* disconnects the transmitting magnet TRM and at armature *ip2* completes the outgoing loop circuit including relays D and I so as to prepare the distant switch for 70 operation.

Upon receipt of the first series of impulses, 75

relay A de-energises intermittently and repeats the impulses at armature a_1 to the receiving magnet RCM of the impulse correcting device in parallel with relay C. It should be mentioned that the ratchet wheel 9 is indicated in Fig. 1 by the disc R, the gear wheel 13 by the disc T and the pin-carrying frame member 12 by the disc F. The number of pins provided may conveniently be 40 which will render the device capable of dealing with at least four digits at a time. The operation of the magnet RCM serves to drive the disc R thus putting additional tension on the spring by which it is connected to the disc T. This disc is prevented from rotating because it is held against the pin displaced from the fixed disc F at the end of the last call. The disc R is driven by the magnet RCM on the release drive principle so that before it commences to move relay C will have operated and at armature c_1 will have energised the marking magnet MKM corresponding to magnet 2 in Figs. 2-5, which tilts the lever 39 carried by the disc R clear of the pins. Relays B and C are provided with copper slugs to enable them to remain continuously energised during the stepping of disc R and accordingly the lever 39 is held clear of the pins during the whole movement corresponding to the first digit. No effect is yet produced however on the disc T.

At the end of the first digit the disc R will have advanced a number of steps equal to the number of impulses in the train and when relay C releases after its slow period, the marking magnet MKM is de-energised and allows the lever 39 to restore thereby pushing a corresponding pin from this disc into the path of disc T. Furthermore contacts mkm operated by the marking magnet will now close and since the off-normal springs ON close as soon as the disc R rotates away from disc T, a circuit is now completed for operating relay BY which locks up at armature by_2 independent of contacts mkm . Armature by_1 prepares a circuit for the transmitting magnet TRM, armature by_3 short circuits relays D and I in order to provide better impulsive conditions for repeating regenerated impulses into the apparatus at the distant exchange, armature by_4 applies a further guard earth to the P conductor, armature by_5 provides a further earth to hold relay IP, while armature by_6 completes a circuit from earth, off-normal springs ON, fixed disc F and pin, insulated reset pin 24 in disc T, contacts trm , and armature by_6 to short-circuit relay IP.

After a short interval relay IP releases and at armature ip_1 completes a circuit to energise the transmitting magnet TRM which thereupon moves the reset pin 24 to restore the movable pin in the disc F against which it is resting. At the same time the contacts trm remove the short-circuit from relay IP which immediately re-operates and releases the transmitting magnet at armature ip_1 . The transmitting magnet thus only operates for a period sufficiently long to push the pin back to normal. Disc T is now freed from disc F and it rotates due to the coil spring 17 until it comes up against the stop pin on disc F which was displaced at the end of the first digit. Meanwhile the second digit will be in process of reception and the disc R will therefore be advanced to a further position where a further pin in disc F is pushed forward to register the second digit.

It will be recalled that the disc T is actually in the form of a gear wheel 13 adapted to drive under the control of a suitable adjustable speed

governor 19 a cam 29 controlling the impulse springs IMP in the outgoing loop circuit and it will be clear therefore that by a suitable adjustment of the governor 29 it can be arranged that the regenerated impulses are of the correct speed 5 while the shape of the cam determines that they are of correct ratio.

Each series of impulses is stored mechanically in the manner described and after the receipt of the first series is completed reception and transmission take place simultaneously but quite independently of each other. The interdigital pause between the regenerated series of impulses is controlled by the release time of the relay IP and the operation and release of the magnet TRM. 15

When all digits have been received, the disc R finally comes to rest and when all regenerated digits have been transmitted the disc T catches up with the disc R and comes to rest against the final stop pin. In this position the off-normal 20 springs ON again open and unlock relay BY and armature by_3 removes the short-circuit from the impedance bridge relays D and I. The repeater circuit is now prepared for speech transmission and when the called subscriber at the distant exchange removes his receiver, the battery feed to relays D and I over the junction from the distant exchange is reversed. The right-hand winding of the polarised relay D is already energised from armature il and since the current flow in the two 30 windings of the polarised relay D is now in the same direction, relay D will operate and at armature dr_1 operate relay DR. Armatures dr_1 and dr_2 reverse the battery potential on the incoming negative and positive conductors to give a supervisory signal to the calling apparatus and armature dr_3 operates relay BB. This relay at armature bb_1 shunts armature ip_2 in the negative speaking conductor, at armature bb_4 locks itself up, at armature bb_2 further guards the P conductor, at armature bb_3 opens the impulsive circuit to the regenerating mechanism in order to prevent its operation should the calling subscriber accidentally operate the dial during conversation, and at armature bb_5 disconnects relay IP. 45 Relays A, B, D, I, DR and BB remain operated during the conversation.

When the calling subscriber replaces his receiver, relay A releases and disconnects relay B. Relay B releases after a slight interval and opens 50 the circuit of relays D and I and the former disconnects relay DR. After a further short interval, relay DR releases and disconnects relay BB. When relay BB releases after its slow period, the guard earth is removed from the P conductor to 55 release the preceding switches and free the repeater for further use. Relay DR is made slow operating by the use of a copper slug at the armature end in order to prevent it being operated should relay D be affected by any kicks due 60 to condenser discharge. If the called subscriber replaces his receiver first, relays D, I and DR are released and relay BB is then dependent only on relay B.

Should the calling subscriber replace his receiver before the mechanism has completed the transmitting operation the incoming P conductor is guarded at armature by_4 until such time as the mechanism is ready to deal with another call.

It will be appreciated that there is no necessity 70 to restore the impulse correcting device to normal since it is arranged to resume its operation on the next call from the position it occupies at the termination of the previous one.

It is to be understood that the invention is not 75

limited to the details of construction employed, as modifications may be made in the impulse receiving arrangements and in the impulse transmitting means without departing from the spirit 5 of the invention. For instance, a number of receiving devices instead of one may be employed each adapted to handle a single digit and a number of transmitting devices may be employed instead of one, in which case appropriate transfer 10 arrangements would require to be provided to render each device operable successively in proper order and at the proper time. At the same time it is believed that the general construction shown provides a simple and more economical construction 15 as it will simplify the mechanism and circuits. Similarly the length of the interdigital pause may be controlled by separate timing arrangements. Moreover though the invention has been described with reference to a straightforward impulse repeater for regenerating direct current impulses, it is not limited to this use. For instance it could readily be arranged to convert alternating current impulses which might be of voice frequency into direct current impulses 20 and vice versa. Furthermore the mechanical regenerator might be employed in an incoming repeater instead of an outgoing repeater as shown in Fig. 1.

The use of this invention extends the impulsive limits obtainable in that it may be used over 30 long distance lines, having a mechanism at each end if both way working is employed. Owing to the lightness of construction, the mechanism can successfully respond to a train of mutilated pulses 35 and subsequently send out corresponding regenerated pulses which are correct as regards ratio and speed.

We claim:

1. In a repeater, a plurality of movable members each having a normal position, means for moving appropriate ones of said members from their normal positions in accordance with the number of impulses in each of a series of trains of incoming impulses, means for transmitting 45 outgoing impulses in successive trains, said moved members determining the number of outgoing impulses in each transmitted train, means for restoring each moved member to normal position, and each member on restoration enabling 50 the transmission of the next train of outgoing impulses to take place.

2. In a repeater, the combination of an electromagnet operated in response to incoming impulses, a setting device operated in accordance 55 with the operations of said electromagnet, a plurality of marking devices, a particular one of said marking devices selected in dependence upon the position occupied by the setting device at the end of a train of impulses and would to effect a marking, and a second electromagnet for initiating 60 the transmission of a train of outgoing impulses in accordance with said marking.

3. In a repeater, a single registering device operated in accordance with a plurality of incoming 65 trains of impulses, means for transmitting corresponding outgoing trains of impulses in accordance with the operated register device, and means for delaying the transmission of each outgoing train of impulses until the corresponding incoming train of impulses is fully received and registered.

4. In a transmitting system, a repeater operated successively in response to a plurality of incoming trains of impulses to store the same, means in said repeater for transmitting outgoing 70

trains of impulses of the same number, each outgoing train of impulses delayed until the corresponding incoming train has been fully stored, and an electromagnetically-controlled device for determining the instant each outgoing train of 75 impulses is to be transmitted.

5. In a repeater, a member operated responsive to successive trains of incoming impulses, a second member following the same path as said first member for controlling the generation of similar trains of outgoing impulses, and means for delaying the operation of said second member dependent upon the duration of the corresponding train of incoming impulses.

6. In a repeater, a registering means operated responsive to trains of incoming impulses, a device adapted to be driven at a constant rate of speed, an impulse generator controlled by said device for generating outgoing impulses, obstructing means moved into the path of said device in 20 response to the operation of said registering means to effect a marking corresponding to the end of each incoming impulse train, and means for restoring the moved obstructing means to initiate operation of said device and generator 25 a predetermined time after said obstructing means was moved by said registering means.

7. In a repeater, a single register device operated one step for each incoming impulse received and successively operated in accordance with a 30 plurality of incoming trains of impulses to register the same, means for transmitting corresponding outgoing trains of impulses in accordance with said registrations, said register device being effective to register an incoming train of 35 impulses during the time a previously registered incoming train is being transmitted.

8. In a repeater, a registering member operated step-by-step in response to incoming impulses, an impulse sender for transmitting outgoing impulses, a stop member carried by said sender moved over a path corresponding to that of the registering member, and a pin displaced in the path of said stop member by said registering member coming to rest after its step-by-step 45 operation at the end of a series of incoming impulses for controlling the operation of said sender.

9. In a repeater as claimed in claim 1 including an electromagnet for restoring said movable 50 members, a circuit for said magnet, and means for closing a point in said circuit in response to the completion of the transmission of an outgoing train of impulses.

10. In a repeater as claimed in claim 7 having 55 means for initiating the transmission of the outgoing trains of impulses after the registration of the first incoming train of impulses.

11. In a repeater as claimed in claim 1 including means for automatically introducing a pause 60 of predetermined length between successive trains of outgoing impulses.

12. In a repeater as claimed in claim 5 including means for releasing said second member to enable the same to follow said first member to 65 generate said outgoing impulses after the termination of the corresponding incoming impulse train.

13. In a repeater, a registering member operated step-by-step in response to incoming impulses, an impulse sender for transmitting outgoing impulses, a stop member carried by said sender moved over a path corresponding to that of the registering member, a plurality of pins arranged in the path of said registering member, 70

and a magnet energized throughout each train of incoming impulses for lifting said registering member clear of said pins and deenergized at the end of each train to cause said registering means to displace a corresponding pin in the path of said stop member.

14. In a repeater as claimed in claim 13 including means on said stop member for arresting the movement thereof in response to said last means engaging said displaced pin, and means for operating said last means to restore said displaced pin to continue the movement of said stop member.

15. In a repeater as claimed in claim 13 including a stepped head mounted on said stop member for arresting the movement of said stop member in response to said head engaging said displaced pin, and an electromagnet for axially moving said stepped head to restore said displaced pin in response to its energization.

16. In a repeater as claimed in claim 13 including a circuit for controlling the transmitting operation, said circuit completed over said displaced pin.

25 17. In a repeater as claimed in claim 13 including an electromagnet and means for operating said registering member one step on each de-energization of said electromagnet, and a circuit for energizing said registering member lifting 30 magnet completed prior to the deenergization of said stepping electromagnet.

35 18. In a repeater, means for registering incoming trains of impulses, means for transmitting corresponding trains of outgoing impulses having predetermined speed and ratio, said last means including a centrifugal governor for predetermining the speed of said outgoing impulses, and an adjustable governor cup having a conical interior for altering the braking effect on said 40 governor in case the position of said cup is altered.

45 19. In an impulse transmitter, means for transmitting impulses, a centrifugal governor for determining the speed of said impulse transmission, and an adjustable governor cup having a conical interior for altering the braking effect on said governor in case the position of said cup is altered.

50 20. In a register sender, a movable member having a plurality of positions, movable pins arranged in the path of said member, there being a movable pin for each position of said member, means for moving said member one step from one position to its next position in response 55 to each incoming impulse received, said member displacing the pins corresponding to the positions occupied by said member at the end of each series of incoming impulses, a sending member operable in the path of said pins, said sending member having a position corresponding to each position of said movable member, means for operating said sending member, means controlled by said displaced pins for stopping said sending member in the positions corresponding to the displaced pins, means for restoring said dis-

placed pins in response to said sending member being stopped in said positions, and an impulse transmitting means controlled by said sending member for transmitting a series of outgoing impulses each time said sending member is operated 5

10 21. In a register sender, a movable member, means for moving said member one step for each incoming impulse received and for successively moving said member to a plurality of positions 15 to register a plurality of digits in response to the receipt of a plurality of incoming series of impulses, a second movable member, means for successively moving said second member to corresponding positions, impulse transmitting means 20 for transmitting a digit in accordance with each successive movement of said second movable member, and means whereby said first member may be in motion to register a subsequent digit at the same time that said second member is in motion to transmit the prior registered digit.

25 22. In a register sender, a first movable member, means for successively moving said first member to a plurality of positions in accordance with the number of impulses in each incoming series to register a plurality of incoming digits in response to the receipt of a plurality of series of incoming impulses, a second movable member, means responsive to said first means for successively moving said second member to positions 30 corresponding to the successive registering positions assumed by said first member in registering said incoming digits, said second member moving concurrently with said first member or otherwise after the first registration by said first 35 member, and an impulse transmitting means for transmitting an outgoing digit in accordance with each successive movement of said second member.

40 23. In an impulse receiving and transmitting device, a pair of coaxially rotatable members, means controlled by the received impulses for causing one of the members to be rotated and to mark certain of the positions occupied during said rotation, and means for causing the other member to be rotated and to control the transmission of impulses in accordance with the positions marked by the first member.

45 24. In an impulse receiving and transmitting device, a series of elements each having a normal position, a member capable of being associated with the elements of said series in sequence responsive to incoming impulses and controlled in accordance with the incoming impulses to displace certain of the elements when associated therewith, a second member, motor means for the second member controlled by the incoming impulses to cause the second member to be associated with the elements of said series in the same sequence after an interval of time and to 60 be influenced by displaced ones of said elements thereby to control the transmission of impulses.

JOHN WILLIAM McCLEW.
CECIL ROBERT WOODLAND. 65
